UNITED STATES PATENT OFFICE.

LAWRENCE E. JOHNSON, OF ST. JOSEPH, MISSOURI, ASSIGNOR TO SPECIALTY SHOE MACHINERY & TOOL CO., OF ST. JOSEPH, MISSOURI.

STRING-NAILER.

1,134,617.

Specification of Letters Patent.

Patented Apr. 6, 1915.

Application filed August 20, 1910. Serial No. 578,191.

To all whom it may concern:

Be it known that I, LAWRENCE E. JOHNSON, citizen of the United States, residing at St. Joseph, in the county of Buchanan and State of Missouri, have invented certain new and useful Improvements in String-Nailers, of which the following is a specification.

My invention relates to shoe nailing machines and refers especially to that type of apparatus designed to use nails which are connected in a continuous string and supplied to the feeding mechanism in this form.

The chief objects of the improvements which constitute the subject matter of this application for patent are:—To provide an efficient mechanism adapted to handle nails in string form, and to permit the use of different sizes of nails in the same machine without changing the mechanism, it being only necessary to lead the end of the selected nail string to its proper channel, a plurality of such strings being suitably arranged in the machine so that any one of them may be selected as desired.

Other objects of this invention are to provide a positive nail feed whereby the nail string is advanced step by step to bring the nails composing it successively into a position where they are within the path of the nail severing device, the arrangement being such that only a single nail at a time can be thus positioned; to furnish means for severing the nail thus selected, providing therefor efficient shearing mechanism whereby the nails are successively severed from their connection with the string and removed to the nailing point.

Further objects are to provide efficient nail driving mechanism whereby the severed nail is forced with certainty and precision into the work, which is suitably arranged and solidly held by proper devices; to furnish independently operated means whereby the shoe into which the nails are to be driven is fed by moving it predetermined distances, so as to properly space the driven nails apart; to provide a piercing implement or feed awl whereby the necessary nail holes are formed in the shoe sole, said awl having this function in addition to being the operative member for the shoe feed, and to furnish means for gaging or guiding the shoe so that the line of nails will be properly located relatively to the sole margin.

I accomplish the desired results by em-

ploying the apparatus illustrated in the accompanying drawings which form a part of this application, the details of construction being shown in the following assembled and detailed views:—

Figure 1 is a side elevation of the upper portion of a shoe nailing machine embodying my improvements, one of the arms carrying the drive shaft being broken away; Fig. 2 is a top plan view of the mechanism illustrated in Fig. 1; Fig. 3 is a side elevation of the mechanism shown in Fig. 1 viewed from the opposite direction, one bearing for the drive shaft being broken away and the reels removed; Fig. 4 is a front end elevation of the parts shown in Fig. 1; Fig. 5 is a bottom plan view of the shoe feed; Fig. 6 is an end view of the parts shown in Fig. 5; Fig. 7 is a sectional view taken on the line 7—7 of Fig. 5; Fig. 8 is a detail view of the cam-wheel which operates the shoe feed; Fig. 9 is a view showing the nail guide removed; Fig. 10 is a sectional view taken on the line 10—10 of Fig. 9; Fig. 11 is a fragmentary view showing a front elevation of the nail feeding and driving mechanism; Fig. 12 is a view showing a portion of the nail feeding and driving mechanism in side elevation; Fig. 13 is a bottom plan view showing the throat and operating arm therefor in detail; Fig. 14 is a fragmentary sectional view taken on the line 14—14 of Fig. 12; Fig. 15 is a side elevation of a portion of the shoe feed, showing a modified form of cam; Fig. 16 is an enlarged view of the end of the nail feed arm and dog; Fig. 17 is an edge view of the modified form of cam shown in Fig. 15, for operating the shoe feed; Fig. 18 is a fragmentary view, enlarged, showing the extreme end of the central bracket arm; Fig. 19 is a side view of a modified form of a nail guide block, provided with a nail feed stop; Fig. 20 is a side elevation of the block shown in Fig. 19, with the feed stop attachments removed; Fig. 21 is a front elevation of the parts shown in Fig. 19, with the feed dog omitted, and Fig. 22 is a fragmentary view of the upper end of the nail stop plate, viewed from the inner side.

Referring to the details of the drawing, the numeral 25 indicates a base plate from which rise two integral arms 26, spaced apart and surmounted by boxes 27 forming bearings for a drive or cam shaft 28. Upon the middle of this shaft is mounted a cam disk 110

29, having its side faces formed with cam grooves for operating various arms and levers, said arms, levers and grooves being hereinafter described in their co-operative relation. Attached to the base plate 25 in the median line and extending upward and then forward is a central bracket arm 30 which forms a support for the nail feeding and severing devices and the nail driving mechanism and to this arm are also attached the various levers which operate the above mentioned devices. Projecting laterally from the bed plate 25 is an extension 31 having attached thereto a reel arm 32, projecting upward and forward and bearing upon the extremity a plurality of reels 33, upon which the nail strings 34 are wound, as shown in Fig. 2.

The several operations of feeding the nail string, severing the nails from their connection thereto and placing the severed nail within the path of the driver, will now be described in detail.

The nail string 34 is led from the reel 25 directly to a channel or conduit 35, formed in a guide block 36, Figs. 3 and 9. This block is supported on the forward end of the arm 30 by a lateral projection or slide arm 37 which is fitted to move in a horizontal groove 38 formed in the side of said arm 30. The slide arm 37 is held in place by a latch plate 39 secured to the arm 30 by screws 40. In order to accommodate different sizes of nails, there may be several of the said conduits 35, and four such channels are illustrated in the drawings, arranged parallel and extending in an inclined direction, as shown in Figs. 9 and 10. These conduits are formed by cutting in one face of the block 36 the requisite number of grooves of suitable dimensions to accommodate the nail strings, the bottoms of the grooves being inclined relatively to the face of the block. The conduits are completed by inserting in 45 these grooves thin filling strips 41, secured by pins 42. These strips close the fronts of the grooves only, leaving spaces behind them to form the conduits 35 down which the nail strings are fed, as aforesaid. The 50 said conduits, being inclined at different angles, come out upon the face of the guide block at different distances from the bottom of the block as shown in Fig. 9 these distances corresponding to the length of the 55 nail for which that particular slot is arranged.

Provision is made for adjusting the slide arm 37 and attached block 36 when slid laterally, so as to bring the feed conduits 35 successively to the working point, by the following devices:—Extending vertically in the side of the arm 30, from the groove 38, is a second groove 43 (Fig. 12) in which is 60 slidably mounted a latch 44 (Fig. 3) having its lower end adapted to engage notches 45

in the upper edge of the said slide arm 37. The latch is held in its groove by the said latch plate 39 and is urged downward by a coiled spring 46. The latch is operated by a pin 47 projecting through a slot in the latch plate.

By reference to Fig. 10, in which the nail string 34 is indicated in dotted outlines, it will be observed that the first nail in the string occupies the groove 35^a, and since the latter is made deep enough to accommodate the body only of the nail, as a consequence the lip of the nail head will project beyond the face of the block, as indicated at 48, and this projecting lip lies in the path of a nail feed member consisting of a plunger 49 (Fig. 11) rectangular in cross section and arranged to slide vertically in a groove 50 (Fig. 12) formed in a plate 51 secured to the end face of the frame arm 30. One side 52 of the groove 50 is cut away as indicated at 53, Fig. 14, and the plunger has one corner rabbeted as indicated at 53, Fig. 12, so that one of its faces will be flush with the edge face of the plate 51 and thus be in contact 54 with the inner surface of the guide block 36, opposite the group of nail conduits 35. The lower end of the said plunger is furnished with a recess 54, Fig. 16, and in this is arranged a dog 55, pivoted to the plunger at 56, and held in an extended position by a spring 57, so that one lower corner 58 of the dog will ride against the guide block when the plunger is at the upper part of its stroke, and when at its lower position the said corner 58 will engage the projecting lip 48 and carry the nail downward to the end of the stroke made by the plunger. As the nail is still attached to the string 34, this downward movement will bring the next nail into the position previously occupied by the first one, and when the plunger again ascends the spring 57 will yield to allow the dog 55 to pass the lip. The said plunger or nail feed 49 is operated by a feed bar or rock lever 59, Fig. 3, pivoted to the arm 30 by a bolt 60, which passes through ears 61 integral with said arm. The rear end of the rock lever 59 is provided with a roller 62 which engages a cam groove 63 in the side of the cam disk 29, while the forward end has a slot or notch 64 engaging a roller 65 attached to the upper end of the nail feed 49.

When the nail is fed downward by the mechanism above described, it is still attached to the nail string, so that the next step is to sever the nail from the string. This is accomplished by means of a movable throat comprising a shearing plate 66 (Figs. 1 and 3) secured to the under side of a shearing lever 67. This lever is bent at the points 68 (Fig. 13) to form an offset and is pivoted to the under side of the arm 30 by a shouldered screw 69 so as to move in a

horizontal plane, and when the said lever is operated, the plate 66 will coöperate with the lower edge of the arm 30, as indicated at 70, to sever the nail from its attachment 5 to the string. The rear end of the said shearing lever 67 passes back along the side of the arm 30, Fig. 2, and is supplied with an anti-friction roller 71, which engages the face of the cam disk 29 near the periphery, 10 so that it travels outside the location of the cam groove 68, as shown in Fig. 3. The face of the disk in the path of the said roller 71 is depressed for a part of the circumference, as indicated at 72, the depth of the 15 recess thus formed determining the movement of the throat at the opposite end of the lever 67. A spring 73, supported upon a bracket 74, causes the roller 71 to hug the face of the disk, and as the shearing movement takes place while the roller 71 passes from the lowest to the highest part of its path, it will be seen that the action of the 20 jaw 66 is positive, and consequently effective.

Lying parallel with and just behind the 25 feed plunger 49 is a similar plunger 75, (Figs. 11 and 12) hereinafter designated the nail drive or driver. This driver is slidably mounted in a groove 76 in the arm 30. The said groove is reduced in area below and is 30 closed in by the plate 51 to form a nail duct 77. The said nail driver 75 has attached to its lower end an extension forming a driver bar 78 which is fitted to reciprocate in the duct 77, with the movement of the driver. 35 The latter is operated by mechanism analogous to that which controls the nail feed hereinbefore described. A rock lever 79 (Figs. 1, 2, and 3) bent near the middle and having its opposite portions symmetrically 40 curved, is pivoted on the bolt 60 between the ears 61. The forward end is formed with a notch or slot 80 to operatively engage a roller 81 attached to the upper end of the driver. The rear end of the said lever 79 45 extends to a point directly over the center of the disk 29 and upon the side opposite to that upon which the lever 59 is arranged and is furnished with an anti-friction roller 82 which engages a cam groove 83 formed in 50 said disk.

To render the nailing mechanism above described effective, it is necessary to have co-operating shoe feeding means, incidentally combining therewith means for piercing the 55 work to facilitate the entrance of the nail. Secured to the side of the central frame arm 30, upon the side opposite to the feed lever 59, is a rock lever 84 (Fig. 1) pivoted on a screw 85. The rear end of this lever terminates in a curved extension or arm 86 bearing 60 upon its extremity an anti-friction roller 87, which is engaged by a cam wheel 88 mounted on the shaft 28 alongside the disk 29 but with an interval between them sufficient to 65 permit the play of the lever 79. Attached

to the lever 84 is a bracket 89, which carries a rock arm 90, pivoted at 91. The rear end of the said arm is provided with an anti-friction roller 92 adapted to engage the cam wheel 88 while the forward end is connected 70 by a spring 93 to an eye 94 on the rock lever 84, the tendency of the spring thus being to carry the opposite end of the lever away from the cam wheel 88. To counteract the action of the spring 93 when desired and 75 hold the roller 92 in position to be engaged by the said cam wheel, a stop 95 is pivotally mounted upon the bracket 89 beneath the rear end of the said arm. This stop is made eccentric and provided with a pin or handle 80 96 by means of which the said stop 95 can be turned to different angular positions to adjust the arm 90, relative to the cam wheel 88, or by turning the said stop half a revolution the said arm may be thrown to a position 85 out of the path of the cam, rendering it inoperative. The rollers 87, 92, are not in the same plane, but each has its separate path of travel on the face of the cam wheel and the periphery of the latter has raised 90 portions 97, 97^a, lying in the path of the rollers 87 and 92, respectively, and these raised and depressed portions are so related that when the arm 86 is moved away from or toward the center of the cam, the co-operating arm 90 will move in the opposite direction, thus rocking the lever 84 upon its center 85. Mounted upon the said lever 84 parallel with its upper edge and co-extensive therewith is a rock-shaft 98 which 100 passes at the rear end through a box 99 formed in the bracket 89, and at the forward end extends through a bearing in a box or bracket 100 formed integral with said lever 84. Attached to the rear end of said rock-shaft is a curved arm 101 having a roller 102 which projects into the path of a lug 103, extending radially from the periphery of the cam 88, and having its advancing 105 edge inclined, the purpose of this mechanism 110 being to rock the said shaft at each revolution of the cam shaft 28 by the engagement of the roller 102 by the lug 103 a spring 104 returning the shaft 98 to its initial position when released. The opposite end of the 115 said shaft is provided with a crank-arm 105, having a crank-pin 106 which engages a swinging feed lever 107 pivoted at 108 to the said bracket 100. The lower end of the feed 120 lever 107 is provided with a pin or feed awl 107^a which projects downward directly above the work. The function of this awl is twofold; it pierces the sole of the shoe to form a hole into which the nail is driven and, before it is withdrawn from the sole, the feed lever 107 is rocked, thus swinging the awl on its center and feeding the shoe forward a measured distance before the awl is withdrawn. The latter is thrust into the 125 sole by the action of the elevated portion 97^a 130

of the cam wheel 88, which engages the arm 90, and the lug 103 will strike the arm 101 and rock the shaft 98 forward before the awl 107^a has been withdrawn. The feed 5 may be varied by adjusting a screw 109 which limits the throw of the crank arm 105 in one direction. By the arrangement above described the feeding of the work is accomplished with positiveness and precision by 10 mechanism having an independent action.

Arranged beneath the nail feed and driving mechanism attached to the forward end of the frame arm 30, is the shoe guide for determining the location of the line of nails 15 relatively to the margin of the shoe sole. This comprises a plate or shelf 110 (Figs. 5 and 6) having rearwardly projecting curved supporting arms or brackets 111 secured to the frame arm 30 by a bolt 112. Attached to 20 the underside of the shelf 110 is a spring plate 113, and the said shelf is recessed to receive a guide bar 114, having a down turned lip or lug 115, forming an abutment against which the edge of the work is held during 25 the nail driving procedure. This bar is adjusted by a lever 116, pivoted to the under side of the plate 110 by a screw 117, and having a slot 118 through which a pin 119, fixed in the bar 114, projects. The said 30 plate 113 bears against the bar 114 with sufficient force to hold the bar from moving under ordinary circumstances, but will allow the said bar to be readily shifted by means of the lever 116. The said bar is held in 35 proper alignment by means of a pin 120 fixed in the spring plate 113 and projecting into a groove 121 in the under face of the bar. The plate 113 has a slot 122 to permit the 40 passage of the feeding awl.

In Figs. 15 and 17 a modified means for 45 operating the rock lever 84 is shown. In this case the extension arm 86 is omitted and the cam wheel 87 replaced by a cam disk 123. An arm 124 is substituted for the arm 90 and has an anti-friction roller 125, projecting into a cam groove 126, formed in the side face of the disk 123. The arm or lever 124 is adjusted, as was the arm for which it is substituted, by the eccentric stop 95, but 50 no spring is needed as the action of the cam groove 126 gives a positive movement to the lever in both directions, and when the stop 95 is moved to its inoperative position, the action of the cam will be to simply rock the 55 lever 124 on its pivot without affecting the lever 84. The periphery of the cam is cut away to form an inclined portion 127 adapted to operate the rock shaft 104 in the same manner as the lug 103 previously described. 60 The lower margin of the said lever 124 is provided with a projection or stop 128 which forms a shoulder adapted to engage the margin of the bracket 89, so that when the cam 95 is turned to throw the roller 125 to oper-

ative position, the said lever will be held 65 with a sufficient degree of firmness.

It is desirable to provide means for stopping the nail feed before the end of the nail string is reached for the reason when the string end has left the storage spool or reel 70 33 and only a few connected nails remain in the nail channel the friction of the dog 55 on its upward or return stroke, as it drags over the last nail may tend to carry with it the light fragment of string remaining, and so 75 interfere with the proper feeding of the nails. The same condition may occur when the nail string breaks at any point, a possibility which may arise from the bending of the string while being wound upon the reel. 80 In Figs. 19, 20, 21, and 22, is shown a mechanism designed to remove the difficulties above mentioned. The modified guide block 85 36^a is furnished with a groove or rabbet 129, and the edge of the block is recessed to 85 form a seat for a guard plate 130, which partly closes in the side of the said rabbet or channel 129. This plate is pivoted at 131 and is furnished with a spring 132 which tends to urge the lower end of the plate outwardly against the feed dog 55, and when not restrained in this direction it will push the said dog back out of operative position and thus stop the feeding of the nails. This 90 action is normally prevented by a flange 133 95 formed on the front margin of the guard plate 130 at its top and projecting over the front of the channel 129. The upper end of said flange projects beyond the plate and is bent forward forming an angle or shoulder 100 134 which is brought into engagement with the nail string 34 when the latter occupies the channel opposite said shoulder, and when in this position the lower end of the plate 105 130, will be held back so as not to interfere with the action of the feed dog 55. Whenever the nail string is nearly used up so that the upper end is below the shoulder 134, the 110 action of the spring 132 will rock the plate far enough to throw the dog 55 out of action. A flat detent spring 135 is secured at 115 its upper end to the face of the guide block 36^a by a screw 136, while its lower end projects into the path of the nail heads as they 120 pass down the channel 129, the latter being widened by a lateral recess 138 to insure the proper working of the spring. As the nail string 34 is fed downward by the action of the dog 55 the detent spring 135 will yield to allow the nail heads to pass, but on the 125 return stroke of the feed dog the lower end of the said spring will engage the adjacent nail head and prevent the nail string from being carried backward. This positive action of the said detent spring takes place 130 during either position of the guard plate

The operation of the machine, described

- in a general way, is as follows:—The shoe upon which a sole is to be nailed is placed upon the anvil (not shown) with the edge of the sole in contact with the guide lug 115. 5 If not previously adjusted the bar 114 is now moved by means of the handle or lever 116 until the awl 108 will pierce the sole at the required distance from the margin. The selected nail string having been inserted into 10 its corresponding duct 35 and the latter brought to the operative position by shifting the guide block 36, the cam or drive shaft 28 is set in motion by operative connection (not shown) from a drive pulley 139 mounted on the shaft 28 with any suitable source of power. When the said shaft rotates, its first action will be to move the nail feed plunger 49 downward, the dog 55 engaging the overhanging lip 48 of the nail 15 which lies in the groove 35a 40 and carrying the said nail downward in the manner hereinbefore described. At the cessation of this movement the shearing lever 67 will be 20 swung by the action of its cam 72, severing the nail and carrying it to a position directly beneath the driver bar 78. In the meantime the lever 84 has been rocked by the cam 88 so as to thrust the awl 108 into the sole, and the shaft 98 rocked to feed the shoe one 25 step. The lever 84 is of this instant rocked back to its initial position, withdrawing the awl, which is returned by the spring 104, to its first position. The driver now descends, forcing the severed nail into the puncture 30 made by the awl, and is quickly returned to the beginning of its stroke thus completing the cycle of movements required for feeding and driving a single nail. It will be understood that when the first nail is fed 35 downward and severed it will leave the succeeding nail in the groove 40 in position to be engaged by the feeding dog 55, and a further rotation of the cam shaft 28 will cause a repetition of the movements above 40 described a nail being driven at each revolution of the said shaft.
- Having thus described my invention what I claim as new is:
1. In a shoe nailing machine, the combination with a frame, and means for supporting nail strings in roll form, of an adjustable nail guide having a plurality of differently formed nail conduits therein, nail feeding means comprising a reciprocating member, a dog yieldingly mounted on said member and adapted to successively engage the heads of the nails, a cam shaft, a cam-disk mounted on the cam shaft, and an operative connection between said disk 50 and the reciprocating member.
  2. In a shoe nailing machine, the combination with a frame, a plurality of reels adapted to hold nail strings, means for feeding the nails, nail severing means, and a
  3. nail driver, of shoe feeding means, comprising a rock-lever, and a rock-shaft mounted on said lever, a cam-shaft, a disk on said shaft, an operative connection between said disk and the nail feeding means, the nail severing means and the nail driver, a cam-wheel on said cam-shaft and an operative connection between said wheel and the shoe feeding means. 65
  4. In a shoe nailing machine, the combination with a frame, a plurality of reels adapted to hold nail strings, a nail feed, a nail shear, and a nail driver, of shoe feeding means, comprising a rock-lever, a rock-shaft mounted on said lever, an awl operatively connected with said shaft, a cam shaft, a cam-wheel on said cam-shaft, cams on said wheel, and arms on said rock-shaft engaging said cams. 75
  5. In a shoe nailing machine, the combination with a frame, a plurality of reels adapted to hold nail strings, nail feeding means, nail severing means, and nail driving means, of shoe feeding means, comprising a rock-lever, a rock-shaft mounted on said lever, a spring for the shaft, an awl operatively connected with said shaft, a cam-shaft, a cam-wheel on said cam-shaft, arms on said rock-lever engaging the periphery of said wheel at diametrically opposite points, and means for adjusting one of said arms. 80
  6. In a shoe nailing machine, the combination with a frame, a plurality of reels adapted to hold strings of connected nails, nail feeding means, nail severing means, and nail driving means, comprising a rock-lever, a rock-shaft mounted on said lever, a spring for the shaft, an awl pivoted on said lever, a crank arm on said shaft engaging said awl, a cam-shaft, a cam-wheel on the cam-shaft, a fixed arm on said rock-lever engaging said wheel, a movable arm on said lever also engaging said wheel, and means for adjusting said movable arm. 85
  7. In a shoe nailing machine, the combination with a frame, reels adapted to hold strings of connected nails, nail feeding means, nail severing means and nail driving means, of shoe feeding means comprising a rock-lever, a sole piercing member pivoted on said lever, a rock-shaft mounted on said lever and adapted to swing said piercing member on its pivot, a cam-shaft, means on said cam-shaft for operating said rock-lever and rock-shaft, and a shoe guide. 90
  8. In a shoe nailing machine, the combination with a frame, reels adapted to hold strings of connected nails, a nail feeding member, a nail severing member, a nail driver and a sole piercing member, of a cam-shaft, a cam-disk mounted on said shaft, 95

cam grooves on the opposite faces of said disk, levers pivoted on said frame and engaging said cam grooves, operative connection between said levers and the said nail feeding and nail driving members, and means independent of said cam-disk for feeding the shoe.

In testimony whereof I affix my signature in the presence of two witnesses.

LAWRENCE E. JOHNSON.
